DESIGN FOR A NIGHTGOWN

Sylvia S. Pedlar, New York, N. Y.

Application August 13, 1936, Serial No. 64,392

Term of patent 3½ years

To all whom it may concern:

Be it known that I, Sylvia S. Pedlar, a citizen of the United States of America, residing in Manhattan, county of New York, and State of New York, have invented a new, original, and ornamental Design for a Nightgown, of which the following is a specification, reference being had to the accompanying drawing, forming part thereof, wherein,

The cross-hatched areas extending down the front portion of the nightgown, represent lace inserts.

I claim:

The ornamental design for a nightgown, substantially as shown, and described.

SYLVIA S. PEDLAR.
